US00D920767S

(12) **United States Design Patent** (10) Patent No.: **US D920,767 S**
Lee (45) Date of Patent: **** Jun. 1, 2021**

(54) **WALL PLATE COVER FOR ELECTRONIC DEVICE**

(71) Applicant: **ELAGO COMPANY CO., LTD.**,
Goyang-si (KR)

(72) Inventor: **Chanwoo Lee**, Goyang-si (KR)

(73) Assignee: **ELAGO COMPANY CO., LTD.**,
Goyang-si (KR)

(**) Term: **15 Years**

(21) Appl. No.: **29/760,034**

(22) Filed: **Nov. 27, 2020**

(51) LOC (13) Cl. **11-05**

(52) U.S. Cl.

USPC **D8/352; D13/156**
